UNITED STATES PATENT OFFICE.

JOHN HEINEL, OF ROCKFORD, ILLINOIS.

BODY STRUCTURE FOR TRAVELING BAGS, CASES, AND THE LIKE.

1,346,495.

Specification of Letters Patent. Patented July 13, 1920.

Application filed January 27, 1919. Serial No. 273,317.

To all whom it may concern:

Be it known that I, JOHN HEINEL, a citizen of the United States, residing at Rockford, in the county of Winnebago and State 5 of Illinois, have invented certain new and useful Improvements in Body Structures for Traveling Bags, Cases, and the like, of which the following is a specification.

This invention relates in general to bag- 10 gage, and has more particular reference to traveling bags and cases and similar articles, especially with regard to the materials involved in the manufacture of the body structure of such articles.

15 It is well known that traveling bags and cases, due to the severe usage to which they are ordinarily subjected, are very quickly and easily damaged. This is particularly so when such articles are made of imitation 20 leather and other inexpensive materials for the purpose of lightness in weight and for other well known reasons, and even those of a more expensive construction are comparatively short-lived when used continu- 25 ously in traveling.

It is the purpose of my present invention 30 to obviate many of the objections following from the present method of manufacturing traveling bags and cases, and to provide a generally improved and novel body structure for articles of this character, possessing exceptional qualities which will be presently mentioned.

In furtherance of this general object, my 35 invention contemplates the provision of a body structure for traveling bags and cases and other articles of the character in mind, consisting of a number of plies of different materials glued or otherwise cemented or 40 united together and constituting in effect, a unitary body structure characterized by its lightness, durability, flexibility, etc., which will be apparent from the following disclosure.

45 My invention consists, generally stated, in the provision of a body structure for the purpose described comprising a facing of suitable material, such for example as genuine or imitation leather, canvas or other fabric, etc.; a reinforcing body united with the inner side of the facing material and consisting of strands or strips of fibrous growth, such as cane, reed, willow or the like, arranged close together and glued or otherwise 50 55 united to the facing; and an inner fabric glued or suitably united with the inside of

the strip material. This three-ply structure forms a composite body appearing on its face as simply composed of the particular facing material used, but which possesses 60 the qualities of its reinforced fibrous body, and exceptional qualities of durability and flexibility. The body structure is also comparatively light of weight, due to the fibrous reinforcing material and to the fact that the 65 facing material may be of considerably lighter weight than ordinarily used. Also the use of the cane or fibrous growth body permits elimination of certain metal framework ordinarily used. Thus with a body 70 structure of the character in mind, an exceptionally strong and durable case may be provided lighter in weight and at less cost than is possible to obtain under the present methods of manufacture in which a case in 75 order to possess the desired qualities of strength and durability must be made of heavy leather and a strong metal framework, which results in an expensive article.

Other objects and attendant advantages 80 will be appreciated as the invention becomes better understood by reference to the following description when considered in connection with the accompanying drawings.

In the drawing, the figure is a perspective 85 view of a suitcase, partially broken away to show the body structure and to illustrate one practical application of my improvements.

As already mentioned my improvements are applicable to traveling bags and cases of 90 various descriptions, and in fact to any case or receptacle to which the body structure is adapted. In the present instance, a suitcase will exemplify the use of my improvements, and it will be noted from the drawing 95 that the suitcase shown is of a conventional type comprising a main body designated generally by character 2, a cover 3 suitably hinged to the body, suitable fastenings for the cover, a handle, and straps, all 100 of which are details having no particular bearing on the invention.

My improvements relate to the formation of and materials used in the body structure, and I prefer that this body shall be of three 105 plies, viz: a facing 4, a reinforcing body 5 and an inner facing or lining 6. The facing 4 may be of any suitable material depending, of course, on the nature, style and cost of the particular bag or case. This facing may be of canvas or any other fabric suitable for the purpose, or of genuine or

imitation leather, or of fabricoid, a material well known in this art. It is practical also to make the facing lighter in weight when used in connection with my improvements, than when such facing constitutes the main body or covering of a case as in the ordinary methods of manufacturing these articles. The reinforcing body 5 is of narrow strip material of fibrous growth, preferably of cane, although reed and willow also serve the purpose very well. The strips or strands are glued or otherwise united to the back of the facing material 4 in close relation as illustrated in the drawing. This reinforced body is preferably lined with a suitable fabric 6 of muslin or other material which may be glued to the cane. A composite body is thus provided which is flexible and possessed of unusual strength and durability by reason of the peculiar arrangement and characteristics of the reinforcing elements. Such material when used in the manufacture of traveling bags or cases will withstand heavy and sharp blows and rough usage which would ordinarily pierce, dent or injure the ordinary case. The body structure is also exceptionally light of weight and is considerably lighter than traveling cases and bags made of heavy grade leather. In the latter instance and in the general manufacture of suitcases in particular, strong metal frames are necessary, but in the use of my improvements the reinforcing structure holds the shape and a metal frame is not necessary, except perhaps at the inside of the cover member 3, where a light metal frame or valance might be used. In the manufacture of suitcases, I prefer to arrange the material so that the strips on the long sides of the case extend lengthwise, as shown, and a single piece of material is used to form the top 7,

side 8 and bottom of the body 2. The ends 9 of this body 2 are arranged so that the fibrous strips extend vertically and the adjoining edges of the parts 7, 8 and 9 may be suitably overlapped and sewed or otherwise secured together. The cover 3 is formed substantially the same as the body 2. Suitable fastenings, handles, corner caps 50 or guards, hinges, etc., and also lining inside of the three-ply body structure may be provided as these elements have no particular bearing on the present invention.

From the foregoing, it will be understood 55 that my improved body structure is adapted for embodiment in traveling bags, cases and receptacles of various descriptions and sizes and also that the materials used in this composite body structure might be varied to 60 suit the particular size, shape and character of the article being manufactured. Hence it should be understood that various changes might be made in the construction, arrangement and selection of materials without departing from the spirit and scope of the invention as expressed in the appended claim.

I claim:

A traveling case formed of a three-ply body comprising a facing material, a lining 70 and an interposed reinforcing body of narrow fibrous or cane strips laid side by side, said plies being united by an adhesive so as to constitute a composite body, the case having sides and ends formed of said composite body, the ends being arranged with the strips running vertically and the side portions with the strips running horizontally, the end edges of said side portions being turned inwardly over and crosswise of 75 the end sections forming angular corners integral with the sides, and stitching uniting the turned over edges and said end sections.

JOHN HEINEL.
